Inventor

Adam Jatho,
By his Attorney,
W. G. Henderson.

UNITED STATES PATENT OFFICE.

ADAM JATHO, OF VICTORIA, TEXAS.

MOSQUITO-CANOPY FRAME.

SPECIFICATION forming part of Letters Patent No. 447,878, dated March 10, 1891.

Application filed November 15, 1889. Serial No. 330,430. (No model.)

To all whom it may concern:

Be it known that I, ADAM JATHO, a citizen of the United States, residing at Victoria, in the county of Victoria and State of Texas, have 5 invented certain new and useful Improvements in Mosquito-Canopy Frames; and I do hereby declare the following to be a full, clear, and exact description of the invention, such as will enable others skilled in the art to 10 to which it appertains to make and use the same.

My invention relates to mosquito-canopies, and has for its object to simplify the construction and increase the strength of the 15 parts and the facility with which they are put together and taken apart; and to such ends the invention consists in the construction and combination of parts hereinafter particularly described and claimed, reference being 20 had to the accompanying drawings; forming part hereof.

Figure 1 is a perspective of a bed with the canopy-frame attached thereto. Fig. 2 is a side view of the upper portion of the frame 25 with parts broken away and others in section. Fig. 3 is a detail view of one form of lock. Fig. 4 is a similar view of another form of lock. Fig. 5 is a rear view of the upper part of the frame, with parts broken away and the 30 upper cross-bar separated from the uprights. Fig. 6 is a view of one form of loop, and Fig. 7 a similar view of another form in which screws or nails may be employed.

In the drawings, the letter A designates the 35 head portion of a bedstead, to the upright posts B of which are attached the loops C, to receive the upright standards D of the canopy-frame, said standards having an offset E at their lower ends to rest upon the top edges of the lower loops, so as to aid in sustaining the standards. The upright standards D are 40 formed on their inside faces with recesses F, having flanges or pins G extending across them to receive the ends of hooks H, projecting from the ends of a cross-bar I, which connecting the standards together at their upper ends. By connecting the upright standards 45 together, as described, the several parts are strongly braced and close and tight joint made between the uprights and cross-bar, with the means connecting them at the joint 50 completely concealed from view. The parts

can also be readily separated by simply tapping upwardly on the lower edge of the transverse connecting-bar.

55

The front faces of the upright standards at their upper ends are also formed with recesses J, having transverse flanges or pins K therein, with which will engage hooks L, formed on the rear of brackets M. These 60 hooks enter the recesses and pass back of the pins or flanges, and are then dropped, so that their hook ends will engage the pins and hold the brackets to their places. They can be 65 readily removed by simply tapping on their under faces, so as to lift them up. It is preferred to secure pins N to the lower portions of the brackets and recesses O in the upright standards to receive them, so as to brace the lower parts of the brackets against side pressure; but such are not absolutely necessary.

70

Instead of the cross-pin in the recesses, I may use merely a plate set across the recess, the plate having a slot in it, but not as deep as the recess in the standard, so that the edge 75 of the plate at the lower end will constitute a flange as the equivalent of the pin for the hook to engage with, as illustrated in Figs. 3 and 4; and instead of a hook of the form shown in Fig. 2 I may use a headed pin, as 80 shown in Fig. 3, the head of the pin serving as the hook, and when such form is used the slot in the plate or the recess may have the upper portion larger than the lower portion, so that the head may enter the larger portion 85 and when dropped down will pass back of the narrower portion, so as to bear against the back of the plate, whose edges at the reduced portion serve as the equivalent of the transverse pin, as shown in Fig. 3, or the form of 90 hook shown in Fig. 4 may be used; but the preferred form of hook is that illustrated in Fig. 2, where it is set inside the bracket or cross-bar and pivoted therein with the hook portion projecting outside, so as to enter the 95 recess and engage the pin. When pivoted as described, the hook has a slight movement that will accommodate it to slight variations in positions of parts resulting from shrinkage or otherwise, and will thus always insure easy 100 attachment and detachments of parts and at the same time preserve a close joint.

The upright standards at a point above the brackets on their front faces are provided

with threaded cavities or holes P, designed to receive the threaded ends of the side rods or bars Q, the opposite ends of which side bars are also threaded and designed to enter 5 threaded holes in the ends of the front cross bar or rod R. The threads on one end of the side rods are right threads and those on the other left threads, so that by bringing the ends of the rods into the threaded holes in the 10 upright standards and front cross-bars and then turning the side bars the upright standards and front bars will be simultaneously drawn together, and in that way not only are the standards and front cross-bar strongly 15 and securely held together, but they are brought together without straining any part of the whole frame and with the greatest facility.

The frame constructed in accordance with 20 the foregoing description is simple and strong in its several parts, and easily put together and taken apart by persons having no experience in such matters, and can be compactly packed for storage when not required for use.

I am aware that it is old in bedsteads to 25 form the side pieces with hooks to engage pins in recesses formed in the head and foot pieces of the bedstead; also that it is old to provide chairs with rounds having right and 30 left threads to screw into threaded holes made in the legs of the chair; also that it is old in mosquito-canopies to have a corner bracket between the upright standards and the side bars, and also to have the side and cross bars 35 secured to an upright standard by pins, and bracing corner brackets secured to the upright standards and side bars by pins. I, however, make no claim to any such features, but only to the particular construction specified 40 in the following claim, which has as essential elements, among other features, the particular construction of upright standards therein specified and the combination there-

with and with the threaded side bars of the brackets applied in the manner specified to 45 be held from movement out of place by the side bars and to support the side bars while permitting them to be screwed in and out, as illustrated.

Having described my invention and set 50 forth its merits, what I claim is—

A mosquito-canopy comprising the standards D, each formed on its inside face with a recess provided with a cross projection for a hook to engage and on its front face with a 55 recess provided with a cross projection, and at a point above said last recess with a threaded aperture, a cross-bar I, extending from one standard D to the other and provided at its ends with hooks entering the recesses formed in said standards and extending down back of the cross projections of said recesses, the brackets M, provided with hooks entering the recesses in the front of the standards D and extending back of the cross projections thereto, the top faces of the brackets being below the threaded apertures in the standards, the front cross-bar having threaded apertures, and the side bars resting upon said brackets so as to turn thereon, and having 60 their ends threaded and entering the threaded apertures of the standards and of the front cross-bar, said thread being right and left, so that by turning the side bars the standards and front cross-bar will be simultaneously 65 adjusted to and from each other, said bracket serving to support said side bars during their adjustment, substantially as and for the purposes set forth.

In testimony whereof I affix my signature in 70 presence of two witnesses.

ADAM JATHIO.
